(57) **CLAIM**

The ornamental design for a water purification media device,
as shown and described.

DESCRIPTION

FIG. 1 is a top perspective view of the water purification
media device according to the present disclosure;

FIG. 2 is a first side view of the water purification media
device of FIG. 1, the opposite sides being a mirror image
thereof;

FIG. 3 is a second side view of the water purification media
device of FIG. 1, taken ninety degrees from the view of FIG.

2, the opposite sides being a mirror image thereof;

FIG. 4 is a top view of the water purification media device
of FIG. 1; and,

FIG. 5 is a bottom view of the water purification media
device of FIG. 1.

The broken lines in the drawings illustrating boundaries that
form no part of the claimed design.
